J. H. MEACHAM.
SHOE SUPPORT.
APPLICATION FILED MAY 13, 1915.

1,253,624.

Patented Jan. 15, 1918.

UNITED STATES PATENT OFFICE.

JOHN H. MEACHAM, OF ROCHESTER, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SUPPORT.

1,253,624.

Specification of Letters Patent. Patented Jan. 15, 1918.

Application filed May 13, 1915. Serial No. 27,818.

To all whom it may concern:

Be it known that I, JOHN H. MEACHAM, a citizen of the United States, residing at Rochester, in the county of Strafford and State of New Hampshire, have invented certain Improvements in Shoe-Supports, of which the following description, in connection with the accompanying drawings, is a specification, like reference characters on the drawings indicating like parts in the several figures.

This invention relates to pulling-over machines and particularly to the shoe supporting mechanism of such machines.

15 In the manufacture of shoes having white and colored uppers there has occurred more or less discoloration of the heel portion of the uppers at the points where the heel rest engages the shoe. In the operation of the 20 machine the shoe is positioned against the sole rest and the upper is seized and pulled and then the heel rest, which is provided with a V-shaped recess in its front face, is advanced into engagement with the shoe, 25 the rest being laterally movable so that it can adapt its position laterally to the position of the shoe heel, and thereafter the rest rigidly holds the heel portion of the shoe against displacement during the succeeding 30 operations of the machine upon the shoe. The construction and arrangement for producing these results is fully explained in United States Letters Patent No. 1,029,387, granted June 11, 1912, on application of 35 Ronald F. McFeely. It is at the points on opposite sides of the middle of the heel where the inclined side walls of the rest engage the shoe that the discoloration is liable to occur on colored goods. To overcome this 40 difficulty is the object of this invention, and this is accomplished as herein shown by providing the heel rest with a liner having such characteristics as will prevent bruising, marring, staining or otherwise discoloring 45 shoe uppers. Preferably the liner will be so constructed and arranged that it can be readily removed and replaced so that different liners may be used with different colors of shoe uppers and thereby avoid staining 50 one shoe by transferring to it coloring material which has been rubbed off from another shoe. With this particular object in

view one embodiment of the invention comprises a liner which may be made at a very small cost so that an ample number of them 55 may be kept on hand and they may be thrown away when they become soiled.

Another function which the liner may serve in accordance with another feature of this invention is that of affording a support 60 adapted to the size and shape of the shoe which is to be rested upon it. There is an obvious practical advantage in equipping the machine with a single heel rest, and this rest and its operating mechanism have been 65 arranged as explained in the said McFeely patent for self-adaptation to various lengths of shoes. It is found, however, that in pulling-over children's shoes, the heel rest of said patent does not afford adequate 70 support against downward displacement of the heel portion of those small shoes, and for dealing with this situation there has been produced the heel rest construction disclosed in United States Letters Patent No. 75 1,113,085, granted Oct. 6, 1914 on application of Orrell Ashton. In accordance with the feature of the present invention here under consideration, the advantages of a readily replaceable liner are combined with 80 the advantages of the last mentioned patent, the same being embodied in a readily removable liner constructed and arranged to prevent injury or discoloration of delicate upper stock and to present, when in position 85 upon the heel rest of the machine, appropriately arranged supporting surfaces to uphold the heel portion of a child's shoe, the surfaces being preferably arranged at a smaller angle than the angle between the 90 work engaging surfaces of the rest for large shoes so that the child's shoe will be gripped more tightly.

These and other features of the invention will appear more fully from the following 95 detailed description when read in connection with the accompanying drawing, and will be particularly pointed out in the appended claims.

Figure 1 is a side view of a pulling-over machine provided with one embodiment of my invention, and shows in dotted lines the position of the shoe being pulled over by the machine;

Fig. 2 shows in perspective the heel rest of the machine with one form of my liner attached thereto;

Fig. 3 shows in perspective another form of liner attached to the heel rest;

Fig. 4 is a perspective view, partly in section, of the heel rest provided with another form of liner having additional functions; and

Fig. 5 is a plan view of Fig. 4.

In Fig. 1 of the drawings the numeral 2 indicates the heel rest of a pulling-over machine of the type disclosed in the McFeeley patent referred to. The heel rest 2 is mounted upon arms 4 which are pivoted at 6 for swinging movement laterally of the shoe and are also pivoted at 8 to swing rearwardly to bring the locking means at 10 in contact when pressure is applied to the rest 2 in a downward and rearward direction. The heel rest is mounted on a slide 12 which is moved upwardly and forwardly when the machine starts to bring the rest into contact with the shoe held by the grippers 14, 16 and to sustain the shoe during the pulling-over operation. Mechanism not shown is provided for locking the slide 12 against rearward movement.

The liner for the heel rest 2 may comprise the construction shown in Fig. 2, in which 20 is a skeleton frame fitted to the inner face of the rest 2 and having top portions 22 formed as hooks which engage over the top edge of the rest to keep the skeleton frame from dropping down, and other extensions 24 which are adapted to engage the lower edge of the rest to hold the frame yieldingly in place upon the rest. If desired, the frame may have lateral portions 26 formed to engage over the side edges of the rest. This, however, is not essential. On the rear face of the skeleton frame 20, which comes next to the rest, is cemented a canvas backing 28, and on the front face of the rest, with which the rear portion of the shoe comes into contact, is cemented a fabric lining 30, for example of hard felt, the felt serving to prevent staining or other injury to the delicate upper materials. As the heel rest moves forward into contact with the shoe and one of the inclined faces of the liner comes in contact with the heel portion of the shoe, the felt surface of the liner will slide over either side of the heel portion of the shoe with which it may come in contact without undue friction, and will move laterally with the rest until it finds its proper location with both bearing faces in contact with the rear portion of the shoe, whereupon, when further pressure is applied, it becomes locked in its lateral position.

In Fig. 3 a somewhat modified form of construction is shown, in which the frame for holding the felt, instead of being skeletonized, extends substantially over the en-

tire bearing faces of the rest, and is provided with attaching means 22, 24 substantially similar to that shown in Fig. 2. In this construction the felt or other covering of the attachment is allowed to extend over the edges of the frame, and is secured to the back thereof so as to prevent any tendency for the felt to be displaced by the rubbing action of the felt against the shoe as the rest is brought into operative position. Preferably, the edge of the frame is bent rearwardly as at 32 and the felt brought over and tucked under the rearwardly bent portion of the frame as at 34, the felt and frame then being secured in assembled relation by crimping down the edge of the frame upon the edge of the felt, as shown.

The liner may comprise a light aluminum frame 36 as shown in Fig. 4 which preferably has a continuous inner face, but is honeycombed at the back or otherwise provided with intersecting ribs, whereby it is rendered light and strong. Holes 38 may be provided along the outer wall of the attachment, which serve not only to diminish the weight of the attachment but enable it to be readily grasped by the fingers of the operator for removal and replacement. The attaching hooks 22 are formed integral with the frame 36, as in the other constructions shown, but the members 24 for yieldingly holding the attachment in position are preferably formed as separate spring members riveted at 40 to the frame 36. The inner faces of the frame 36 are arranged at an angle more acute than are the faces of the rest proper, as shown in Fig. 5, and consequently this liner is better adapted to sustain the rear end of small shoes than one having a less acute angle, since the rear part of the shoe wedges more tightly into the angle and offers more resistance to the pull of the toe gripper which tends to turn the shoe last about the sole rest as a fulcrum. A fabric cover similar to those shown in Figs. 2 and 3 is provided. This cover may be attached to the frame 36 by slots or grooves 41 formed in the top and bottom of the frame 36 to accommodate the attaching means as shown.

Having thus described my invention, what I claim as new and desire to secure by Letters Patent of the United States is:

1. In a pulling-over machine, the combination with a heel rest, of a liner therefor presenting a non-rigid shoe engaging surface and spring clasps for engagement around the upper and lower edges of the heel rest.
2. In a pulling-over machine, the combination with a heel rest, of a liner therefor comprising a sheet metal frame having spring clasps for engagement with the edges of the rest, a facing, and a backing of fabric secured to the frame.

3. In a pulling-over machine, the combination with a heel rest having faces inclined to each other, of a liner therefor comprising a frame presenting toward the shoe faces arranged at a less angle to each other than those of the heel rest to afford vertical support for the heel end portion of the shoe, and a non-rigid shoe engaging cover detachably secured to said frame.
- 10 4. In a pulling-over machine, the combination with a heel rest, of a liner for the inner faces of the rest, said liner being detachably secured to the rest and having a non-metallic face secured to said liner to prevent injury by staining of the parts of shoes which contact with the liner, the work contacting faces of the liner being arranged at a less angle to each other than are the faces of the rest which they line.
- 15 5. In a pulling-over machine, the combination with a heel rest, of a liner comprising a non-corrodible covering for the inner or work contacting faces of the rest, and attaching means for holding the liner to the rest comprising means on the liner arranged to engage the upper edge of the rest and re-
- 20
- 25
- 30
- 35
- 40
- 45
- silient means to engage under the lower edge of the rest.
6. In a pulling-over machine, the combination with a heel rest, of a liner comprising a composite lining for the inner faces of the rest, said lining including a fabric layer and a metallic layer, said layers being cemented together, and resilient attaching means on the metallic layer for detachably securing the lining to the rest.
7. In a pulling-over machine, the combination with a heel rest having work-engaging faces arranged at substantially right angles to each other, of a liner for the rest, the work contacting faces of the liner being constructed and arranged at an acute angle to the faces of the rest and intersecting in a line extending substantially in the direction of the back seam of a shoe held in said rest so that the heel portion of a small shoe will be gripped and held frictionally against vertical movement.

In testimony whereof I have signed my name to this specification.

JOHN H. MEACHAM.
